UNITED STATES PATENT OFFICE

154,650

DESIGN FOR A COSMETIC DISPLAY DEVICE

John H. Wright, Chicago, Ill., assignor to Consolidated Cosmetics, Chicago, Ill., a partnership composed of James L. Younghusband and Howard Younghusband

Application June 10, 1948, Serial No. 146,886

Term of patent 14 years

(Cl. D80—9)

To all whom it may concern:

Be it known that I, John H. Wright, a citizen of the United States of America, residing at 430 North Michigan Avenue, Chicago, Illinois, have invented a certain new, original, and ornamental Design for a Cosmetic Display Device, of which the following is a specification, reference being had to the accompanying drawing, forming part thereof.

Referring to the drawing, Fig. 1 is a front elevational view of a cosmetic display device, embodying my new design; Fig. 2 is a top plan view; Fig. 3 is an end elevational view and Fig. 4 a rear elevational view of the same.

I claim:

The ornamental design for a cosmetic display device, substantially as shown.

JOHN H. WRIGHT.
